UNITED STATES PATENT OFFICE.

NORMAN A. FULLER, OF YAMHILL, OREGON.

LOADER.

1,337,896.

Specification of Letters Patent. Patented Apr. 20, 1920.

Application filed May 27, 1918. Serial No. 236,840.

To all whom it may concern:

Be it known that I, NORMAN A. FULLER, a citizen of the United States, residing at Yamhill, in the county of Yamhill and

5 State of Oregon, have invented certain useful Improvements in Loaders, of which the following is a specification, reference being had therein to the accompanying drawing.

The present invention has reference generally to improvements in that class of inventions known as loading and unloading, and more particularly relates to loaders especially, though not necessarily, adapted for loading manure.

15 The primary aim and object of this invention contemplates the provision of novel co-operative conveyers, one of which is adjustable relative to the other and operably connected thereto so that they may cooperate 20 with each other in elevating the material being loaded.

It is an equally important object of this invention to provide novel supporting means on the truck body which is turnable with respect to the truck body so that the conveyers 25 may be positioned transversely on the truck body and readily and effectively extended to assume an operative position.

As an additional object, the invention contemplates the provision of novel loading means operably connected to the elevating means for loading the material on the elevating conveyers.

More particularly, this invention embraces the provision of novel means for raising and lowering the movable conveyer on the supporting means so that the movable conveyer may be adjusted in various positions with respect to the ground.

40 As a further improvement, the invention includes novel motion transmitting means operably arranged between the two elevating conveyers, the mounting of such means being constructed so as to also slidably connect the two conveyers with respect to each other.

A more specific object of the present invention consists in the provision of improved means for sliding the movable conveyer with respect to the stationary conveyer; to provide improved means for actuating the loading forks.

Among the other aims and objects of this invention may be recited the provision of a 55 device of the character mentioned with a

view to compactness, in which the number of parts are few, the construction simple, the cost of production low and the efficiency high.

Other improvements and novel details in 60 the construction and arrangement of the various parts of the apparatus will be brought out more in detail in the description to follow, which for a clear understanding of the invention should be considered in connection with the accompanying drawings, forming a part hereof, and wherein is disclosed for the purpose of illustration a convenient and satisfactory embodiment of the invention.

70 The invention is clearly illustrated in the accompanying drawings, in which:—

Figure 1 is a side elevation of the invention;

Fig. 2 is another side elevation of the invention in position ready for use;

Fig. 3 is a top plan view of Fig. 2;

Fig. 4 is an end elevation looking toward the elevating means;

Fig. 5 is an end elevation looking toward 80 the loading means;

Fig. 6 is an enlarged transverse section taken on line 6—6 of Fig. 1;

Fig. 7 is a perspective detail of the means for slidably connecting the two conveyers; 85

Fig. 8 is a perspective detail of the means for raising and lowering the conveyers;

Fig. 9 is a transverse section taken on line 9—9 of Fig. 2 looking in the direction in which the arrows point; 90

Fig. 10 is a transverse section taken on line 10—10 of Fig. 2 in the direction in which the arrows point.

Similar characters of reference are employed in all of the above described views 95 to indicate corresponding parts.

Referring now, more particularly, to the accompanying drawings there is provided a supporting truck or vehicle consisting of a main stationary platform 1 from which depend bolsters 2 made rigid with respect to the platform by braces 3. A rear axle 4 is carried by the rear bolster while the front axle 5 is connected to the front bolster for turning movement. Ground wheels 6 are 100 journaled on the respective ends of the axles while a tongue 7 extends from the front axle. A secondary turning platform is now provided and consists of a plate-like body 8 on the respective side edges of which are 105 110

carried guides 9 disposed to lie above the sides of the main platform 1 when the loader is in a position for transportation as indicated in Fig. 1. Suitable fastening means 5 10 extend through the body 8 and platform 1 for turnably connecting the secondary platform and the main platform while annular bearing bands 11 are carried by the adjacent bases of the two platforms to facilitate the turning movement of the secondary 10 platform with respect to the main platform. The inner faces of the guides 9 are provided with opposed longitudinal grooves 12 in which are slidably mounted longitudinally 15 extending ribs 13 carried by the outer side faces of rack bars 14, for a purpose as will presently appear.

With a view toward providing the improved stationary conveying means relatively high uprights 15 are mounted at the front ends of the guides 9 while short standards 16 are mounted adjacent the opposite side edges of the plate-like body 8. Side plates 17 are rigidly connected adjacent the 20 upper ends of the uprights 15 and the standards 16 and are arranged in opposed relation with respect to each other and inclined toward the center of the guides. A shaft 18 is journaled transversely to the upper ends 25 of the side plates 17 and carries a roller 19. A transverse shaft 20 is journaled adjacent the lower end of the plate 17 and also carries a roller similar to roller 19. A conveying apron 22 operates about the rollers 30 and carries transverse slats 23.

Suitable means have been provided for transmitting rotary motion to the stationary conveying means. In accomplishing this purpose a longitudinal shaft 24 has its respective ends journaled in bearings 25 carried between the standards and the uprights. A pulley wheel 26 is carried by the shaft 24 while a belt 27 operates thereabout and is connected to a suitable source of power for 40 transmitting suitable rotary motion to the shaft 24. A beveled gear 28 is carried adjacent the front end of the shaft 24 and meshes with a relatively large beveled gear 29 carried by a transverse shaft 30, the respective ends of which are journaled adjacent the lower ends of the uprights 15. A sprocket wheel 31 is also carried by the shaft 30 while a chain 32 operates thereabout and is also trained about another 45 sprocket wheel 33 carried by the upper shaft 18. By this arrangement it will be appreciated that when the shaft 24 is rotated owing to the gears 28 and 29 which are in mesh with each other, the shaft will be rotated and by reason of the sprocket wheels 31 and 33 and the chain 32, rotary motion will be imparted to the shaft 18 so as to actuate the conveying apron 22 causing the upper lay to move upwardly.

60 65 As intimated, an improved movable con-

veyer has been provided for coöperating with the stationary conveyer in elevating the material to be loaded. In reducing this feature of the invention into practice, two relatively long opposed side plates 34 are employed. A shaft 35 is journaled through the upper ends of these side plates while a roller 36 is carried thereby. Over this roller operates a slatted conveying apron 37 which is also trained about another roller 38 carried by a transverse shaft 39 journaled in the lower ends of the plates 34.

For the purpose of operatively and slidably connecting the movable conveyer to the stationary conveyer shafts 40 are journaled 80 one end within suitable bearings 41 on the outer face of the upright 16 and the other end in suitable bearings at the top of the stationary conveyer. As will be appreciated upon reference to the drawings this shaft 85 is inclined and a beveled gear 42 is carried by the upper end thereof and meshes with another beveled gear 43 on the shaft 18 so as to rotate the shaft 40 therewith. A bar 44 is mounted on the opposed upright and standard and is arranged in opposed relation to the shaft 40 for the purpose that will presently appear. Arms 45 and 46 are now provided. The arm 45 terminates in a box 46', which is arranged about the shaft 95 40 so as to be slidable thereon. A beveled gear 47 is slidably and non-rotatably connected to the shaft 40 and is positioned within the box so as to be slidable therewith. A fork 48 is formed on the upper end of 100 the arm and is provided with journaled openings for rotatably receiving one end of the shaft 35 while journaled through the box 46 and the fork 48 is another shaft 49, a beveled gear 50 is carried by the lower 105 end thereof and is positioned in the box so as to mesh with the sliding beveled gear 47 whereby when the shaft 40 is rotated through the shaft 18, rotary motion will be consequently imparted to the shaft 49 and 110 by reason of another beveled gear 51 on the upper end of this shaft and within the fork which meshes with a beveled gear 52 carried by the shaft 35 this last mentioned shaft will also be rotated simultaneously 115 with the shaft 18. The bar 46 terminates at one end in a bearing 53 which is slidably engaged on the inclined bar 44 while the upper end of the arm 46 terminates in another bearing 54 in which is journaled the 120 other end of the shaft 35.

Coöperating with the means for operably and slidably connecting the conveyers together is a means for slidably connecting the movable conveyer to the turnable 125 frame. In reducing this feature of the invention to practice short uprights 55 are formed on the outer ends of the rack bars 14. Windlasses 56 are operably connected to these uprights while cables 57 have their 130

respective ends connected to the windlasses and to the lower ends of the respective side bars 34.

Pawl and ratchet mechanisms 57' are operatively mounted on the uprights 55 and the windlasses 56 for maintaining the lower ends of the removable conveyer in various positions of adjustment. By means of the windlasses, the lower end of the movable conveyer of course may be raised and lowered with respect to the ground when the machine is in the position as indicated in Fig. 2. In sliding one conveyer relative to the other a shaft 58 is journaled through the short standards 16 while cog wheels 59 are carried to the respective ends of the shaft 58 and arranged so that the teeth thereof mesh with the teeth of the rack bars 14. A crank handle 60 serves as a means for rotating the shaft so as to consequently slide the rack bars and move the movable conveyer.

As hereinbefore stated, an improved loading means has been provided. In reducing this feature of the invention to practice, longitudinal beams 61 are extended from the side plates 34 to a point substantially intermediate the ends thereof being incidentally arranged longitudinally thereof and projecting beyond the lower end of the movable conveyer. Standards 62 have their lower ends connected to the outer faces of the side plates 34 adjacent the lower ends thereof, and have connected thereto at points approximately intermediate their ends the beams 61 so as to maintain the latter in a horizontal plane. Braces 63 serve to insure the rigid relation between the standards and the plates 34. A cross bar 64 is arranged transversely between the upper ends of the standards 62 and is provided on its upper surface with a plurality of vertical slots 65 for a purpose that will presently appear. A cross beam 66 is arranged transversely between the longitudinal beams 61 adjacent the inner ends thereof while a plurality of supporting rods 67 have their inner ends pivotally connected to the beam 66 and rest in the slots 65 in the cross bar and project beyond. Loader arms 68 have their upper ends pivotally connected to the adjacent free ends of the rods 67 and are pivotally connected to adjacent crank portions 69 of a shaft 70 journaled transversely between the outer ends of the beams 61. The crank portions 69 extend at various angles with respect to the longitudinal axis of the shaft 70 so that when the arms are connected thereto and the shaft is rotated, the arms will move alternately with respect to each other. Forks 71 are carried by the lower ends of the arms 68 and are disposed just above the lower end of the movable conveyer so as to throw the material on the lower end of this conveyer so that it may consequently be conveyed upwardly. The

means for operatively connecting the loader arms to the movable conveyer so that they will operate simultaneously with the conveyer in the present instance consists of a sprocket wheel 72 carried by one projecting end of the shaft 70 and over which is a sprocket chain 73. This chain is also trained about another sprocket wheel 74 carried by the projecting end of the shaft 35.

The mode of operation of the present invention may be reviewed as follows:

Assuming that the parts have been assembled in the manner described, and it is desired to arrange the machine in an operative position to load the material a secondary platform is moved about this pivot 10 so as to be arranged transversely of the main platform 1. The shaft 58 is now rotated by the crank handle 60 so that the cog wheels 59 will operate upon the rack bars 14 so as to slide the rack bars longitudinally of and toward the rear end of the secondary platform inasmuch as the short uprights 55 are carried by the raising and lowering means to the outer or lower end of the movable conveyer. This conveyer will be moved downwardly at an inclination. This action of course is permitted by the arms 45 and 46 which are slidably connected respectively about the shaft 40 and the bracing bar 41. The windlasses 56 are now operated to adjust the lower end of the movable conveyer with respect to the ground. The pawl and ratchet arrangements 57' serve to maintain the parts in adjusted position. The main source of power not shown is now in operation to rotate the shaft 20 and inasmuch as the beveled gear 28 meshes with the beveled gear 29, rotary motion will be transmitted from the transverse shaft 20 to the transverse shaft 30 and by reason of the sprocket chain connection including the sprocket wheel 31 and chain 32 and sprocket wheel 33, the shaft 18 of the stationary conveyer will be rotated and by reason of the roller 19 upon which is frictionally engaged the slatted apron 22, the latter will be actuated so as to move upwardly. During this movement by means of the beveled gears 43 and 42, the inclined shaft 40 will be rotated. Inasmuch as the beveled gear 47 is slidably and yet rigidly connected to the shaft 41 and is in mesh with the beveled gear 50, the short vertical shaft 47 will be rotated. And finally, by reason of the beveled gear 51 on the shaft 47 being in mesh with the beveled gear 52 on the shaft 35, the latter shaft will be rotated and as the slatted apron of the movable conveyer is frictionally engaged about the roller 36, this apron will be also moved upwardly. Actuating simultaneously with the conveyers is the loading means and this operation is effected by the chain 73 which is respectively trained about the sprocket wheel 74

of the shaft 35 and the sprocket wheel 72 on the crank shaft 70. Rotation of the crank shaft of course raises and lowers the arms 68 and inasmuch as they are pivotally connected to the pivotally mounted and vertically swingable supporting rods 67, the arms will have the action of a tedder, and being arranged in proximity to a pile of material, it will throw the material upon the lower end of the movable conveyer, the slatted belt 37 of which will carry the material upwardly and deposit it on the slatted belt 22 of the stationary conveyer which will consequently lift it and thus deposit it in a suitable wagon body.

As many changes could be made in the above construction and many apparently widely different embodiments of this invention could be made without departing from the scope thereof, and it is intended that all matter contained in the above description or shown in the accompanying drawings shall be interpreted as illustrative and not in a limited sense. It is also to be understood that the language used in the following claims is intended to cover all the generic and specific features of the invention herein described and all statements of the scope of the invention, which as a matter of language might be said to fall therebetween.

Having thus fully described this invention, what is claimed as new and desired to be secured by Letters-Patent, is:—

- 35 1. A device of the character described including a supporting platform, supporting means on one end of the platform, a stationary conveyer mounted in the supporting means, an inclined shaft rotatably mounted in the supporting means on one side thereof, an inclined bar on the other side of the supporting means, a motion shaft mounted in the supporting means, motion transmitting means between the main shaft and the conveyer, other motion transmitting means between the conveyer and the inclined shaft, a movable conveyer, means for slidably connecting the lower end of the movable conveyer to the platform, arms, bearings on the respective ends of the arms for operatively supporting the upper end of the movable conveyer and slidably connected to the inclined shaft and the inclined bar, a bearing box carried by one of the arms, and motion transmitting means operatively mounted in the arm and the bearing box for consequently actuating the movable conveyer simultaneously with the stationary conveyer.
- 40 2. An apparatus of the kind described embodying a supporting platform, a relatively stationary conveyer carried by the platform, a relatively movable conveyer carried by the platform, supporting means for

the upper end of the movable conveyer, said supporting means being carried by the stationary conveyer and including a positive driving connection between the two conveyers and means for shifting the movable conveyer along the said platform, the said driving connection the while remaining intact.

3. An apparatus of the kind described embodying a support, a relatively stationary conveyer carried by said support, a relatively movable conveyer carried by said support, means for supporting the upper end of the movable conveyer, said means being carried by the supporting conveyer and embodying a positive driving connection between the two conveyers, rack bars carried by said support on which they are longitudinally movable, said rack bars supporting the movable conveyer adjacent the lower end thereof, and means for imparting longitudinal movement to said rack bars, whereby the movable conveyer may be advanced along the support without interference between the driving connection between the said conveyers.

4. An apparatus of the kind described embodying a support, a relatively stationary conveyer carried by said support, a relatively movable conveyer carried by said support, means for supporting the upper end of the movable conveyer, said means being carried by the supporting conveyer and embodying a positive driving connection between the two conveyers, rack bars carried by said support on which they are longitudinally movable, said rack bars supporting the movable conveyer adjacent the lower end thereof, a rotatable shaft formed with a crank, and pinions carried by said shaft and meshing with said rack bars, whereby the rotation of said shaft by means of the crank may effect longitudinal movement of the rack bars for the purpose specified.

5. An apparatus of the kind described embodying a support, a relatively stationary conveyer carried by said support, a relatively movable conveyer carried by said support, means for supporting the upper end of the movable conveyer, said means being carried by the supporting conveyer and embodying a positive driving connection between the two conveyers, rack bars carried by said support on which they are longitudinally movable, said rack bars supporting the movable conveyer adjacent the lower end thereof, a rotatable shaft formed with a crank, pinions carried by said shaft and meshing with said rack bars to impart longitudinal movement of the same, and manually operable means for raising and lowering the lower end of the said movable conveyer with respect to said rack bars.

In testimony whereof I affix my signature.
NORMAN A. FULLER.
